COMPRESSOR BLADING

John R. Erwin and Leroy H. Smith, Jr., Cincinnati, Ohio,
assignors to General Electric Company, a corporation
of New York

Filed Oct. 29, 1962, Ser. No. 233,661
10 Claims. (Cl. 230—120)

The present invention relates to blading and, more particularly, to compressor blading that has flow augmenting means as an integral part thereof.

One of the problems encountered in axial flow compressors of the types commonly used in jet engines is that of compressor stall. The causes of and theories surrounding compressor stall are not completely understood but can be conveniently summarized by stating that the compressor blading is unable to provide the pressure rise which is required for smooth operation. In other words, the airflow through the compressor is disturbed resulting in pressure pulses and stall of the airflow through the compressor. This can be quite serious in a reaction powerplant since it chokes off operation of the powerplant. Many devices and schemes have been employed to either stop compressor stall or to detect it early enough so that remedial steps may be taken. Other solutions have attempted to put the stall outside the operating range of the powerplant where it is then of no concern. The instant invention is a means of achieving this last solution. The phenomenon of boundary layer is well known and is found in compressor and turbine operation. While applicable to a turbine, the invention is primarily suited for but not limited to compressors and will be described in connection with compressors. In a typical compressor where wall members are formed by a casing and hub respectively with airfoil blades operating in an annulus between the walls, it is known that boundary layer air tends to adhere to the adjacent walls. This results in slow moving low energy air at these walls and a tendency to break down the smooth primary airflow to the blades.

The main object of the present invention is to provide compressor blading employing means to relocate and/or energize the boundary layer air.

Another object is to provide such blading with an attachment that enables the secondary flow to be augmented for moving the boundary layer for better mixing and also assist in turning the fluid in the direction resulting in greater energy addition to the low energy boundary layer fluid.

A further object is to provide a compressor rotor having blading which, by means of an attachment thereto, promotes mixing and turning of the low energy boundary layer and consequent postponement of compressor stall.

Briefly stated, the present invention includes a compressor rotor with a hub to form an inner wall member and an outer casing to form an outer wall member with a row of cambered airfoil blades attached to one of the walls and radially extending towards the other wall. An axially-extending air passage is thus formed containing the blades for passage of air therethrough. The blades are equipped with flow directing vane-like means mounted substantially at right angles to each blade and located adjacent one of the walls. The vane-like means is oriented on the blades so that the flow passing across the concave pressure surface of the blade is directed by the vane-like means toward the adjacent wall.

While the specification concludes with claims particularly pointing out and distinctly claiming the subject matter which is regarded as the invention, it is believed the invention will be better understood from the following

2

description taken in connection with the accompanying drawing in which:

FIGURE 1 is a partial diagrammatic cross-section of a compressor rotor,

FIGURE 2 is a partial view of a pair of rotor blades illustrating the cross-flow between the blades,

FIGURE 3 is a top view taken on the line 3—3 of FIGURE 2,

FIGURE 4 is a view similar to FIGURE 2 showing the addition of the vane-like means adjacent the hub,

FIGURE 5 is a similar view showing a different vane-like means adjacent the hub and the tip of the blade and applied to one side only,

FIGURE 6 is a partial view of a modification using the vane-like means between the blades, and

FIGURE 7 is a plot showing the effect of the vane-like means on the stall characteristics of a typical compressor.

Referring first to FIGURE 1, there is shown diagrammatically a compressor rotor having a hub 10 and an outer casing 11. Both of these form inner and outer wall members respectively. Between these, in the conventional manner, the hub 10 carries rows of rotor blades 12 and casing 11 has similar stator blades 13 each extending radially toward the opposite wall. An axially-extending air passage 14 is thus formed in the conventional manner for the flow of air through the compressor to emerge at higher pressure on the right end of the figure.

Reference to FIGURE 2 showing a pair of rotor blades will illustrate the flow difficulties encountered in a compressor.

It should be understood that the discussion of the invention will proceed with respect to the rotor blades for convenience only and that the same reasoning applies to the stator blades. Since the rotor blades are conventionally cambered airfoils having convex pressure and concave suction surfaces as shown in FIGURE 3, there

are two airflows that normally occur. The first is the primary airflow which approaches the leading edge of the blades and exits from the trailing edge as shown by the

straight arrow in FIGURE 3 and is compressed to a higher pressure in the usual manner. The second flow is called secondary flow and is the motion of the air essentially normal to the main flow or transverse of the passage. This secondary flow comes about due to the pressure fields that exist in the blades and due to the low momentum level of the boundary layer fluid.

As shown in FIGURES 2 and 3, the convex blade surface is normally at a lower pressure, as indicated by the minus sign, than the concave surface. The concave surface is at a higher pressure indicated by the plus sign in both figures.

Because of this pressure difference acting along the boundaries of the walls of the passage, it can be seen that a secondary flow occurs transversely within the passage between adjacent blades and this flow passes from the higher

to the lower pressure region as shown by the curved arrows in FIGURES 2 and 3. This occurs near the walls 10 and 11. It can be seen then that the secondary flow, as shown by the curved arrows in FIGURE 3, has a significant transverse or cross-passage component whereas the

deflection of the main stream of air caused by the blading does not have such a large component. This greater cross-passage or transverse component results in a larger turning and therefore an increased energy addition to the low momentum boundary layer fluid.

The secondary flow, when viewed in the projection of FIGURE 2, is shown by arrows 15. Thus, the secondary flow transports main stream fluid along the concave surface of the blade toward hub 10 and casing 11 within the air passage as shown by the arrows and transports the

boundary layer fluid away from the hub and casing into the center portion of the axial passage between adjacent blades along the convex blade surface. This results in

mixing of the flows. The result of both the turning and mixing is that the boundary layers are energized so that a higher pressure rise across the compressor blading may be accomplished without stall.

The instant invention is intended to augment the turning as well as promote the mixing of the boundary layer into the main air stream. By thus augmenting and mixing, it is possible to obtain higher pressure rise per compressor stage resulting in compressors with fewer stages for a given compression ratio.

In order to augment the turning and promote the mixing the airfoils are provided with flow directing vane-like means 16 as shown in FIGURE 4. These vane-like means 16, which may be flat (i.e., zero camber) but are preferably more cambered as shown, are particularly located at right angles to the blade, whether stator or rotor, so that the main flow passing near the concave surface of the blade is directed toward the adjacent wall. As applied to FIGURE 4, blade 12 has a concave surface 17 and a convex surface 18. Since the main airstream flow shown by arrow 19 creates the secondary flow shown in FIGURE 2, due to the blade pressure surfaces, the vane means 16 is oriented and cambered on the blade 12 to direct the flow down as shown in FIGURE 4 on the concave surface across the passage between the blades and up or radially out as shown on the convex surface of the adjacent upstream blade. Thus, vane means 16 is oriented substantially at right angles on blade 12 to promote flow in this direction. Since the natural secondary flow occurs in this direction, the vane-like members greatly augment this flow but can even reverse the flow if the natural secondary flow is reversed. Furthermore, since the low momentum fluid is actually the boundary layer fluid, the vanes are disposed at a radial location along blade 12 substantially at the surface of the boundary layer of the adjacent wall and thus adjacent the wall. In FIGURE 4 this locates vane 16 at the surface of the boundary layer on wall or hub 19. This is the root portion of rotor blade 12 as shown in FIGURE 4. Similarly, it is possible that the vane-like means 16 may be required on the tip portion of the rotor blade as well. This configuration is shown in FIGURE 5 wherein an additional vane 20 is provided at the tip of the rotor blade near casing 11. The stall characteristics of the particular compressor, such as where stall tends to occur, will determine the location and the need for the vane-like members. If stall tends to occur at the tip portion of the rotor blades, vane 20 would be employed to direct the secondary airflow outward, if at the root portion, vane 16 would be employed to direct the secondary air flow inward, and if at both, both vanes would be employed as mirror images of or in opposition to each other. In other words, the vanes are oriented to augment the transverse flow. Additionally, FIGURE 5 illustrates the use of the vane-like means on only one side of the rotor blade. It may be unnecessary to provide the vane-like means on both sides of the rotor blade. Additionally, various configurations may be provided. As illustrative, the configuration shown in FIGURE 4 is a cambered vane means that extends forward of the leading edge of the blade and the configuration of FIGURE 5 is a cambered arrangement with the vane means extending substantially from the leading edge to the trailing edge only. This latter permits use in multiple stage compressors without interference. Under any circumstances, the vane-like means is provided on the concave surface to promote and augment the transverse flow between adjacent blades from the higher pressure concave surface to the adjacent upstream blades lower pressure convex suction surface.

The vane means may be applied at both the root and tip portions, as shown in FIGURE 5, to direct the flow toward the adjacent wall having a boundary layer. Since the vane is disposed substantially at the surface of the

boundary layer, the term "adjacent wall" is intended to be that wall on which the nearest boundary layer is found.

Referring next to FIGURE 6, a modification is shown wherein the vane-like means 21 may be attached to the inner or outer wall members or both. For illustration means 21 is shown attached to hub 10. In order to augment the flow as desired, means 21 of airfoil shape extends radially into the air passage 14 between the blades. By overcambering and orienting vane-like means 21 at a suitable angle of attack for more turning than blades 12, it can be seen that the secondary flow is augmented. Reference to FIGURE 6 shows the structure and how this occurs. In the absence of vane means 21, a typical air particle on the concave or plus side of blade 12 would follow the path shown by arrow and line 22 as it migrated along the hub toward adjacent blade 12. With vane 21 in place and oriented as shown, the same particle follows the path of arrow and line 23 by first following the convex negative or suction surface of vane 21 and onto the convex or suction surface of vane 12. Greater turning is imparted to the particle resulting in more energy addition to the low energy boundary layer, better mixing, and augmentation of the secondary transverse flow.

FIGURE 7 illustrates the results of employing the vane-like means wherein it can be seen that as the percentage of vanes is increased, a higher pressure rise is obtainable before stall occurs. In other words, the use of the vane-like means permits the stall point of a given compressor to be moved beyond the operating range. The use of the vane means changes the conventional pressure profile and brings in greater velocity gradients to transfer energy more rapidly from the main stream to the boundary layer by moving the boundary layer transversely and promoting mixing and energizing resulting in a greater pressure rise per compressor stage. While the vane-like means have been shown as curved or cambered in FIGURE 4 and substantially flat or near zero camber in FIGURE 5, it is preferable that a more cambered version be used since it provides a stronger action with lower losses although it is not absolutely necessary. Furthermore, it is desirable that the vane-like means be applied at least on the concave surface of the blade, as shown in FIGURE 5, to obtain the desired results.

While there have hereinbefore been described preferred forms of the invention, obviously many modifications and variations of the present invention are possible in light of the above teachings. It is therefore to be understood that within the scope of the appended claims, the invention may be practiced otherwise than as specifically described.

We claim:

1. A rotor having a hub forming an inner wall member, a casing forming an outer wall member, a row of cambered airfoil blade members having convex suction and concave pressure surfaces and being attached to one of said wall members and extending radially toward the other wall member to form an axially-extending air passage through said blades whereby a transverse secondary flow from said pressure surface of each blade to said suction surface of the adjacent upstream blade is set up across the air passage between said blades, and flow directing vane-like means on at least one of said members extending into said air passage and oriented and cambered so that the flow passing near the concave pressure surface of said blade members is directed by said vane-like means toward the convex suction surface of the adjacent upstream blade member to augment the transverse secondary flow.
2. A compressor rotor having a hub forming an inner wall member, a casing forming an outer wall member, a row of cambered airfoil blades having convex suction and concave pressure surfaces and being attached

to one of said wall members and extending radially toward the other wall member to form an axially-extending air passage through said blades, whereby a transverse secondary flow from said pressure surface of each blade to said suction surface of the adjacent upstream blade is set up across the air passage between said blades, and flow-directing vane-like means on, and substantially at right angles to, said blades and adjacent at least one of said walls, said vane-like means being oriented and cambered on said blades so that the flow passing near the concave pressure surface of said blade is directed by said vane-like means toward the adjacent wall and convex suction surface of the adjacent upstream blade.

3. Apparatus as described in claim 2 wherein the vane-like means is radially disposed on said blades substantially at the surface of the boundary layer of the adjacent wall.

4. Apparatus as described in claim 2 wherein the vane-like means is disposed in the root portion of the rotor blades of said compressor rotor.

5. Apparatus as described in claim 2 wherein the vane-like means is disposed at both the root and tip portions of the rotor blades to direct flow near the concave side generally inward at the root portion and outward at the tip portion of said blade.

6. A compressor rotor having a hub forming an inner well member,

a casing forming an outer wall member, a row of cambered airfoil blades having convex suction and concave pressure surfaces and being attached to one of said wall members and extending radially toward the other wall member to form an axially-extending air passage through said blades whereby a transverse secondary flow from said pressure surface of each blade to said suction surface of the adjacent upstream blade is set up across the air passage between said blades,

and flow directing vane-like means on, and substantially at right angles to, each of said blades and adjacent at least one of said walls,

said vane-like means extending on said blade from substantially the leading to trailing airfoil edge and being cambered and oriented on said blade so that the flow passing near the concave pressure side of said blade is directed by said vane-like means toward the

adjacent wall and convex suction surface of the adjacent upstream blade.

7. Apparatus as described in claim 6 wherein the vane-like means is radially disposed on the leading edge of said blades substantially at the surface of the boundary layer of the adjacent wall.

8. Apparatus as described in claim 7 wherein the vane-like means is disposed in the root portion of the rotor blades of said compressor rotor.

9. Apparatus as described in claim 7 wherein the vane-like means is disposed at both the root and tip portions of the rotor blades to direct flow near the concave side generally inward at the root portion and outward at the tip portion of said blade.

10. Apparatus as described in claim 1 wherein said flow directing vane-like means comprises an airfoil member oriented and overcambered beyond said blade members and radially extending from one of said wall members between said blade members.
